SAFETY RAZOR SET CASE

Peter Schladermundt, Bronxville, and William H. Dennerlein, Whitestone, N. Y., assignors to Gillette Safety Razor Company, Boston, Mass., a corporation of Delaware

Application April 5, 1951, Serial No. 14,723

Term of patent 14 years

(Cl. D58—12.6)

To all whom it may concern:

Be it known that we, Peter Schladermundt and William H. Dennerlein, both citizens of the United States, and residing respectively at 8 Park Ave., Bronxville, New York, and 146-08 20 Road, Whitestone, New York, have invented a new, original, and ornamental Design for a Safety Razor Set Case, of which the following is a specification, reference being had to the accompanying drawing, forming a part hereof, wherein:

Figure 1 presents a perspective view of a safety razor set case, showing our new design, in closed position; and

We claim:

The ornamental design for a safety razor set case, substantially as shown.

PETER SCHLADERMUNDT.
WILLIAM H. DENNERLEIN.
